CLAIM

The ornamental design for an infusion pump with rechargeable battery, as shown and described herein.

DESCRIPTION

FIG. 1 illustrates a front-perspective view of an infusion pump with rechargeable battery;

FIG. 2 illustrates a front view thereof;

FIG. 3 illustrates a rear view thereof;

FIG. 4 illustrates a left-side view thereof;

FIG. 5 illustrates a right-side view thereof;

FIG. 6 illustrates a top-plan view thereof; and,

FIG. 7 illustrates a bottom-plan view thereof.

Any broken lines in the drawings are for illustrative purposes only and form no part of the claimed design. Additionally, the infusion pump with rechargeable battery is not limited to the scale shown herein.

1 Claim, 7 Drawing Sheets
